UNITED STATES PATENT OFFICE.

CROSBY FIELD, OF BROOKLYN, NEW YORK, ASSIGNOR TO BRILLO MANUFACTURING COMPANY, INC., A CORPORATION OF NEW YORK.

SCRUBBING DEVICE AND MATERIAL THEREFOR.

Application filed October 8, 1925. Serial No. 61,180.

My present invention concerns metal in ribbon-like or wire-like forms, which may be used for cleaning purposes in the form of pads, wads or rolls or may be woven into 5 metallic fabric, being thus usable in place of the metal wool and metal ribbons described in various other of my co-pending applications.

Heretofore, the only ribbons which have 10 been used for such purposes are very thin in proportion to their width and have very smooth surfaces and edges, apparently due to the rolling or slitting methods by which they are made.

Such smooth edged ribbons are usually 15 about ten times as wide as they are thick, with the result that when wadded or woven, there is practically no tendency to bend edgewise in the plane of the ribbon, but only 20 lengthwise of the ribbon. Consequently, only smooth curves of the material are presented to a surface to be cleaned thereby, unless or until great pressure has been applied to produce a sharp reverse bend. Consequently, 25 a large portion of the ribbon is presented flatwise to the surface to be cleaned while the sharply bent portions become sufficiently sharp and mechanically braced by the reverse bend so that on application 30 of pressure such as is necessary to make the smooth parts effective, these few sharp points tend to dig into and score the surface of the work.

To avoid the above non-uniformity and 35 inefficiency of the scrubbing action and for other reasons, my invention includes making metal ribbons and wires for cleaning pads, wads, fabrics, etc., soap coverings, etc., of such shapes that they will present scrubbing 40 edges or points outward when only slightly curved or even when straight. This makes certain that in a mass composed of a substantial quantity of this material, there will be everywhere presented to the work a large 45 number of efficient scrubbing or scraping edges or points. This makes it entirely practical to use pressure on the scrubbing material only sufficient to make effective the working edges or points that are bearing at the moment. That is to say, the surface of 50 a pad of my material presents such a multiplicity of effective bearing points and edges that the user naturally pays no attention to the few surfaces that may be bearing flatly

on the work, it being immaterial whether the latter are accomplishing anything or not.

The above and other features of my invention will be more evident from the following description in connection with the accompanying drawings, in which

Fig. 1 is a more or less diagrammatic view indicating a pad, cake of soap or the like, in which my scrubbing material may be used;

Figs. 2, 3, 4 and 5 are greatly enlarged 65 views, showing cross-sectional shapes that may be used for the material;

Fig. 6 shows in plan and edge view, a ribbon made in accordance with my present invention;

Fig. 7 is a similar view of a modified form of ribbon; and

Figs. 8, 9, 10, 11 and 12 show other patterns that may be embossed on the surfaces of ribbons or of wires.

In Fig. 1 the massed or wadded ribbon material, 1, is shown in detail at the lower lefthand corner, the dotted lines indicating the complete pad or cake of soap in which such material may be formed.

In Fig. 2 the cross-section is that of a triangle which may be formed by rolling grooves in a sheet until the grooves cut through and separate the material in parallel lengths; or the triangular cross-section 85 may be formed by rolling or drawing wires.

It will be noted that when used for my present purposes, the triangular cross-section does not behave at all like a ribbon which is thin in proportion to its width. 90 This particular section may be flexed with equal ease in any one of three directions and whatever the direction, one of the three edges will be presented directly outward for effective engagement with the surface to be 95 cleaned.

Fig. 3 is a triangle like Fig. 2, so that the tendency to flex in one of the directions is greater than in the other two, although flexing in any one of the three directions is 100 much easier than with a flat thin ribbon.

Figs. 4 and 5 show more unusual forms, but serve to illustrate how sharp thin edges may be formed in lieu of the smoothly rounded edges presented by the ordinary 105 ribbon referred to above.

Fig. 6 shows ribbon which may be of the same general dimensions and materials as

specified in certain of my pending applications; that is to say, the width of the ribbon may be, say, eight to twelve times its thickness, the width being, say, 1/10 to 1/64 of an inch for the thickness of, say, 1/500 to 1/100 of an inch. As my present invention involves utilizing the central portion of the ribbon, I may use ribbons wider than above indicated, and as the embossing or stamping of the ribbon weakens it, to a certain extent, the metal may be thicker if desired. In the particular form shown in Fig. 6, the metal is passed through rolls that stamp it alternately inward and outward on opposite faces, so that the ribbon comprises the smooth marginal portions, 3, 4, separated by the central portion comprising the rectangular protuberance, 5.

The ribbon shown in Fig. 7 is capable of variation as to proportions and materials, as in Fig. 6; but in Fig. 7 the protuberances are in the form of conical projections, 7.

In Figs. 8 to 12 inclusive, the ribbon is merely knurled so as to have a file cut appearance as shown in the drawing.

Where the knurling is squarely transverse, as in Fig. 8, the ribbon will present cleaning ribs or projections lengthwise of the ribbon and cleaning points edgewise of the ribbon. For equal thickness of material, the ribbon will bend more readily and more sharply than will the smooth ribbon heretofore used.

A diagonal knurl, as in Fig. 9, presents cleaning elements analogous to those in Fig. 8, but obviously the flexing of the ribbon will tend to be diagonal.

In Fig. 10, where the knurling is criss-cross, the surfaces will be completely covered with projections for effective cleaning action, no matter how the ribbon is presented to the surface to be cleaned.

Fig. 11 is a composite combining to some extent of certain qualities of the ribbon shown in Fig. 9 with that shown in Fig. 10.

Fig. 12 shows the surfaces as ridged longitudinally, this having the advantage that it preserves maximum tensile strength for the ribbon and is therefore particularly adapted for weaving purposes.

As a preferred and important detail of my invention, I prefer to make the ribbons or threads, not only of relatively fine or thin cross-section, but also of relatively soft non-abrasive metals, of which I prefer copper, aluminum, etc., also various alloys as, for instance, brass, bronze, German silver, Monel metal and ordinary tinsel. An illustrative desirable composition for the metal is, copper 62%, nickel 9 $\frac{5}{16}$ % and zinc 28%,

with less than 1/2% of lead, iron, aluminum, etc.

For the various forms of stamped or embossed ribbons, particularly the types shown in Figs. 6 and 7, it is desirable that the metal be quite ductile. One way of making metal into any of the forms shown is to draw it into wire to get precisely the desired cross-section, after which the wire may be flattened and shaped in embossing rolls. This method is particularly adapted for making indefinitely long lengths of the material, which are desirable for weaving or knitting them into fabric form. This product is equally convenient for wadding or rolling into a ball or mass, either for padding, embedding in solid soap or saturating with liquid soap or mixing with powdered soap.

I claim:

1. A cleaning pad or the like comprising elements rolled so as to form sharp cleaning edges and faces or surfaces, said faces or surfaces being deformed to form additional cleaning elements thereon.

2. A cleaning pad or the like comprising elements rolled so as to form sharp cleaning edges and surfaces, said surfaces being deformed into different designs to form additional cleaning elements thereon.

3. A cleaning device comprising fine flexible linear elements of rolled metal having sharp cleaning edges and surfaces, said surfaces having projections thereon forming additional cleaning elements.

4. A cleaning device comprising fine flexible ribbons of rolled metal having sharp cleaning edges and surfaces, said surfaces being deformed to provide additional cleaning elements thereon.

5. A cleaning device comprising fine flexible ribbons of rolled metal having sharp cleaning edges and surfaces, said surfaces being deformed into designs to form additional cleaning elements thereon.

6. A cleaning device comprising fine flexible ribbons of rolled metal having sharp cleaning edges and surfaces, said surfaces having projections thereon forming additional cleaning elements.

7. A cleaning device comprising fine flexible ribbons of rolled metal having sharp cleaning edges and surfaces, said surfaces being embossed to form additional cleaning elements thereon.

Signed at New York, in the county of New York, and State of New York, this 7th day of October, A. D. 1925.

CROSBY FIELD.
